UNITED STATES PATENT OFFICE.

LOUIS GODDU, OF WINCHESTER, MASSACHUSETTS.

METAL POST FOR WIRE FENCES.

SPECIFICATION forming part of Letters Patent No. 295,918, dated April 1, 1884.

Application filed April 4, 1883. (No model.)

To all whom it may concern:

Be it known that I, LOUIS GODDU, of Winchester, county of Middlesex, State of Massachusetts, have invented an Improvement in 5 Metal Posts for Wire Fences, of which the following description, in connection with the accompanying drawings, is a specification, like letters on the drawings representing like parts.

10 This invention has for its object the production of a strong yet light-weight cast-metal fence-post, and especially to the means for confining the wire in place. The cast-metal part is composed of a thin plate having a flute 15 or trough, or a series of flutes or short troughs, and of one or more backwardly-extended ribs or webs, as will be described. The fluted part referred to is slotted or cut through transversely at suitable intervals to receive the 20 fence-wire, and keep it from sagging, or from being lifted where connected with the post, and the wire is retained in the notch in the said flute by means of a pin placed in the flute and in front of the wire and at right angles to the slot in the flute, there being at each 25 slotted part of the flute a rest for the lower end of the wire locking or holding pin.

Figure 1 represents in rear side elevation a cast-metal post embodying my invention, with 30 fence-wires in place; Fig. 2, a front view thereof, showing how the cast-metal post may be used for a fence partly of wood, if desired; Fig. 3, a section thereof on the dotted line, Fig. 1; Fig. 4, a detail showing a portion of the front side of the post and a wire therein; 35 Figs. 5 and 6, a front view and section of a modification thereof.

The post is composed of a thin cast-metal plate, *a a*, tapered from its widest point 3 to 40 the top 2 of the post, and from the said point 3 to the bottom 4 of the post. The plate *a*, at or near its center, is cast with a concavity or flute, *b*, of greater or less length, as shown in Figs. 1, 2, and 5, and preferably semicircular, and at suitable intervals, according to the 45 distance it is desired to separate the wires *g*.

The said fluted part is slotted transversely, as at *b*, to form a notch for the reception of the wire *g*. The flute *b* is sufficiently deep to give to each of these notches a shoulder below and 50 above the said wire and prevent it from sagging or being lifted at the post. The notch *b* is deep enough to permit the introduction between the wire and wall of the curved or fluted part of the post of a wire locking-pin, *e*, and 55 in the concaved portion of the said flute, just below each notch *b*, I have placed a rest, *f*, for the lower end of the said locking-pin. At the rear side of the plate *a a* is a cast-metal strengthening rib or web, *c*.

Instead of making the part *a* of the post straight, as in Fig. 3, it may be waved in cross-section, as in Fig. 6, and one or two narrower ribs or webs, *c*, may be employed at the rear side.

60 The front side of the post is shown provided with horizontal supports *m n*, which may be used to sustain the ends of wooden rails *o*, which may be attached to the part *a* of the post by suitable screws, *r*, extended through 65 them into holes made in the said post.

65 The rails *o* may have pickets *t* nailed to them, as shown by dotted lines. The projection or enlargement *w* strengthens the post opposite the points where the flutes are slotted.

I claim—

1. The post *a*, having the notched flute or flutes *b*, rests *f*, and rib *c*, in combination with the wires *g* and pins *e*, for retaining the wires in the notched post, substantially as shown 80 and described.

2. A post composed of the part *a a*, the notched wire-receiving flute, and the backwardly-extended rib *c*, substantially as described.

85 In testimony whereof I have signed my name to this specification in the presence of two subscribing witnesses.

LOUIS GODDU.
